DESIGN FOR A WATER CLOSET BOWL

Adolph Hoffman, Metuchen, N. J., assignor to General Ceramics Company, a corporation of New Jersey

Application June 30, 1941, Serial No. 101,806

Term of patent 14 years

To all whom it may concern:

Be it known that I, Adolph Hoffman, a citizen of the United States, residing at Metuchen, in the county of Middlesex and State of New Jersey, have invented a new, original, and ornamental Design for a Water Closet Bowl, of which the following is a specification, reference being had to the accompanying drawing, forming part thereof, wherein:

Fig. 1 is a top view thereof;
Fig. 2 is a side elevation showing a water closet
bowl embodying my said design;
Fig. 3 is a front view thereof.

I claim:
The ornamental design for a water closet bowl,
as shown.

ADOLPH HOFFMAN.
